 PLC(57) **CLAIM**

The ornamental design for a camera, as shown and described.

DESCRIPTION

FIG. 1 is a front perspective view of a camera showing the new design;

FIG. 2 is a front elevational view of the camera;

FIG. 3 is a rear elevational view of the camera;

FIG. 4 is a left side elevational view of the camera;

FIG. 5 is a right side elevational view of the camera;

FIG. 6 is a top plan view of the camera; and,

FIG. 7 is a bottom plan view of the camera.

The broken lines shown in the drawings depict portions of the camera that form no part of the claimed design.

1 Claim, 4 Drawing Sheets(56)
